UNITED STATES PATENT OFFICE.

JEFF D. VAN ATTA, OF MILLERSBURG, OHIO.

CUT-OUT COCK FOR ENGINEERS' BRAKE-VALVES.

SPECIFICATION forming part of Letters Patent No. 678,596, dated July 16, 1901.

Application filed April 29, 1901. Serial No. 57,981. (No model.)

To all whom it may concern:

Be it known that I, JEFF D. VAN ATTA, a citizen of the United States, residing at Millersburg, in the county of Holmes and State 5 of Ohio, have invented certain new and useful Improvements in Cut-Out Cocks for Engineers' Brake-Valves; and I do hereby declare the following to be a full, clear, and exact description of the invention, such as will 10 enable others skilled in the art to which it appertains to make and use the same.

In what is called "double-heading"—that is, where two locomotives are coupled to draw a train—the engineer of the forward engine 15 does the "braking" and the engineer's brake-valve of the rear engine is "cut out." Heretofore in such circumstances it has not been practicable for the engineer of the cut-out engine to observe the degree of pressure and 20 variations of pressure in the train-pipe, and if it became expedient that he assist in the working of the brakes or in recharging the train-pipe he was ignorant as to what might be done or as to what to do. For example, if 25 through necessity or accident the engineer of the forward engine should allow his train-pipe or reservoir pressure to fall below the minimum, so as to render impracticable the proper application of the brakes, the engineer 30 of the rear engine would not be aware of the fact.

The object of my invention, therefore, is to provide the engineer's brake-valve with a cut-out cock and connections that can be 35 manipulated to cut off communication of the main reservoir with the engineer's brake-valve and at the same time establish communication of the train-pipe exhaust with the upper side of the rotary valve in the engineer's brake-valve, permitting the state of 40 the train-pipe pressure to be observed at the usual gages, so that if the engineer of the rear engine observes that it is necessary or expedient he can reopen temporarily this cut-off cock and recharge the train-pipe and auxiliary reservoirs.

In the accompanying drawings, Figure 1 is a vertical sectional view of an ordinary Westinghouse engineer's brake-valve with 45 my cut-out cock and connections added. Fig. 2 is a vertical sectional view of the cut-out cock alone; and Fig. 3 is a sectional view of

the cock-valve alone, taken on a plane indicated by the line xx , Fig. 2.

In the views, 1 denotes the train-pipe collar on the engineer's brake-valve, and 2 is the train-pipe exhaust on that valve.

3 is the collar on the brake-valve, to which the main reservoir is connected, and 4 is my stop-cock valve in said collar. This valve 4 55 is made with three ports, one of them, 4^a , for establishing communication between the main reservoir and the engineer's brake-valve, another, 4^b , to simultaneously open the train-pipe exhaust to the atmosphere, and 60 the third one, 4^c , to establish communication above the cock 4 from the train-pipe exhaust to the upper side of the rotary valve 10 in the engineer's brake-valve when the ports 4^a and 4^b are closed. This port 4^c , however, can under some circumstances be omitted. Connecting the train-pipe exhaust 2 and an opening 5 in the shell or collar containing the cut-out cock is a short pipe 6, a portion of which is shown to be broken out in Fig. 1. The 70 stop-cock valve 4 is furnished with a handle 4^d , by means of which the valve can be turned to bring the ports 4^a and 4^b into or out of alignment with the main-reservoir pipe and the opening 5, respectively, to open or close 75 the passages.

When one engine is used alone, the stop-cock valve 4 is turned to establish communication of the main reservoir through port 4^a with the engineer's brake-valve and to open 80 the atmosphere through port 4^b the exhaust from the train-pipe and simultaneously close the opening 4^c to establish communication of the exhaust with the upper side of the rotary valve 10 in the engineer's brake-valve; 85 but in double heading the engineer's brake-valve of the rear engine is to be cut out, and to do this the cock 4 is turned to cut off communication from the main reservoir to the engineer's brake-valve and simultaneously close the train-pipe exhaust 6 and establish communication of this exhaust with 90 the upper side of the rotary valve in the engineer's brake-valve.

The port 4^c is not necessary with some forms 95 of engineer's feed-valves. Whether this port is necessary depends upon the construction of the feed-valve. In some feed-valves the rotary valve of the engineer's valve can be

balanced by the train-pipe pressure without introducing that pressure into the main-reservoir pipe above the cut-off cock. This will be clearly understood by those acquainted 5 with the construction and operation of engineer's brake-valves.

The "black-hand" gage—that is, the gage indicating the train-pipe pressure—is connected with the pipe 11, while the "red-hand" gage—that is, the gage indicating the main-reservoir pressure—is connected with an orifice (not shown, but well understood) in the collar 3. Both these gages are of course placed in the locomotive so as to be visible 15 to the engineer.

From the construction shown and described it will be observed that the main-reservoir and train pipe pressure can at all times be observed by the engineer whose brake-valve 20 has been cut out and that in case of necessity he can act to avert serious accident.

What I claim, and desire to secure by Letters Patent, is—

1. In an engineer's brake-valve, the combination with the inlet from the main reservoir thereto, of a cut-out cock adapted to 25 open and close said inlet, ports 4^b and 4^c in

said cock, a pipe connecting the train-pipe exhaust of said engineer's brake-valve with said ports, the former port to discharge 30 the exhaust into the atmosphere when the main-reservoir inlet is open and the latter to establish communication of the aforesaid exhaust with the upper side of the rotary member of the engineer's brake-valve when said 35 inlet is closed, substantially as described.

2. In an engineer's brake-valve, the combination with the main-reservoir inlet and train-pipe exhaust thereof, of a cock adapted to simultaneously cut off communication of 40 the main reservoir with the engineer's brake-valve and close the train-pipe exhaust, and when operated to simultaneously establish communication between the main reservoir and engineer's brake-valve and open the ex- 45 haust to the atmosphere, substantially as described.

In testimony whereof I affix my signature in presence of two witnesses.

JEFF D. VAN ATTA.
